UNITED STATES PATENT OFFICE.

JAMES B. ERWIN AND ORLANDO R. ERWIN, OF MILWAUKEE, WISCONSIN.

APPARATUS FOR EXTINGUISHING FIRES.

1,216,789.

Specification of Letters Patent. Patented Feb. 20, 1917.

Application filed November 5, 1915, Serial No. 59,734. Renewed January 8, 1917. Serial No. 141,348.

To all whom it may concern:

Be it known that we, JAMES B. ERWIN and ORLANDO R. ERWIN, citizens of the United States, residing at the city of Milwaukee, county of Milwaukee, and State of Wisconsin, have invented new and useful Improvements in Apparatus for Extinguishing Fires, of which the following is a specification.

10 Our invention relates to improvements in apparatus for simultaneously generating and discharging a quick acting foam upon burning surfaces, set forth and described but not claimed in Letters Patent No. 15 1,128,768, issued Feb. 16, 1915.

Our apparatus consists in the mechanism for commingling quick acting foam producing liquids and the delivery of such foam more rapidly than heretofore, upon a burning surface. The primary object of this invention is to provide the simplest and most efficient means for injecting or introducing a relatively small quantity of sulfuric acid direct, by gravity, into a relatively large quantity of a quick acting foam generating solution, simultaneously at different elevations, and different points, whereby a more thorough and rapid commingling of the two liquids is afforded, resulting in a violent ebullition and instant conversion of the commingled liquids into foam, which rises from the commingled liquids as fast as generated, and is forcibly discharged from the container by its own 35 expansion upon the fire, in greater volume and velocity than by any other means which has heretofore been disclosed.

Our invention is further explained by reference to the accompanying drawing, 40 which shows the general arrangement of one form of our apparatus in vertical section in operative connection with an oil tank also in vertical section.

Connected with the oil tank 1 is a solution tank 2 which is filled nearly full with our foam producing solution 3. The solution tank 2 is directly connected to the oil tank 1 by means of the open spout 4, which spout is secured at one end to the oil tank 50 and at its other end to the solution tank by means of rivets or bolts 5.

The solution tank 2 is closed at its upper end by means of the plate 6, which is bolted to the flange 7, therefor provided on the 55 solution tank 2, by bolts 8. An acid recep-

tacle 9 is pivotally mounted below its center of gravity and in an inclined position, upon trunnions 10 operating in the closed funnel 11, which funnel is attached, as shown, to the plate 6 by the bolts 12. A perforated pipe 13 is connected to the lower end of the funnel 11 and extends to the bottom of the solution tank 2. The acid receptacle 9 is normally held in its inclined position by the latch 14 which latch is pivoted at 15 to the top plate 6 by means of the bracket 16. A cable 17 connects the latch 14 with the weight 18 operating over the pulleys 20, 20. Another cable 21, likewise attached to the weight 18 extends over the tank pulley 20 into the oil tank, and thence over the pulley 20' and from thence to the bottom of the tank 1. The cable 21 is preferably provided with a plurality of fusible links 23, located at short intervals apart, whereby one of such links will be near the surface of the burning oil, regardless of the depth of oil in said tank when ignited. The lower end of the cable 21 is preferably attached to a weight 24, the gravity of which is greater than that of the weight 18. The bracket 25 is supported from the vertical wall of the oil tank near the top. In case of fire one of the fusible links 23 melts permitting said weight 18 to drop, whereby the acid receptacle 9 is inverted, the descending weight 18 acting through the cable 17, releasing latch 14, whereby said acid (sulfuric) will be quickly discharged into the perforated funnel pipe 13, when, owing to the fact that such acid is approximately twice the specific gravity of our foam producing solution, it will rapidly descend in said perforated pipe, and be injected into such solution, simultaneously, at different elevations and different points, resulting in a thorough commingling, whereby the entire solution is quickly converted into foam in large quantities fully adequate to the desired purpose, and capable of developing a pressure sufficient to cause its discharge through a spout to a considerable distance upon a burning surface.

If will be obvious that, while the drawing shows our novel foam generating apparatus in operative connection with an oil tank arranged to automatically extinguish fires therein, we wish to be understood that the same mixing means can be incorporated in our manually operated portable extin-

guishers for discharging the acid at different points and elevations, one form of which is shown in the above mentioned patent.

Having thus described our invention what we claim as new and desire to secure by Letters Patent, is:—

1. The combination with a foam generating tank adapted to contain a suitable liquid solution, means including a receptacle for storing and discharging an acid into said solution, said acid storing and discharging means being located above the solution in said generating tank, a perforated spray pipe connected at its upper end to said acid discharging means, and extending from thence downwardly into the solution in said generating tank, whereby when said acid is released it will be injected simultaneously at different elevations and different points into said solution.
2. The combination with a foam generating tank adapted to contain a suitable liquid solution, means located in said solution for injecting a second liquid simultaneously at different points and at different elevations into said solution, said injecting means for the second liquid being connected to a source of supply exterior to the solution in said generating tank.

3. The combination with a foam generating tank adapted to contain a suitable liquid solution, means located above the solution including a receptacle for storing and discharging an acid into said solution, a perforated spray pipe connected at its upper end to said acid discharging means, and extending from thence downwardly into the solution in said generating tank, whereby when said acid is released it will be injected by gravity simultaneously at different elevations and different points into said solution.

4. The combination with a foam generator provided with a discharge spout for foam, said generator being adapted to receive a suitable liquid solution, means located in said generator for injecting a second liquid simultaneously at different points and different elevations therein together with means for forcibly supplying said second liquid to said injecting means.

In testimony whereof we affix our signatures in the presence of two witnesses.

JAMES B. ERWIN.
ORLANDO R. ERWIN.
